UNITED STATES PATENT OFFICE.

ELISHA PECHEY, OF LONDON, ASSIGNOR TO STEPHENSON, BLAKE & CO., OF SHEFFIELD, ENGLAND.

DESIGN FOR A FONT OF PRINTING-TYPE.

SPECIFICATION forming part of Design No. 21,145, dated November 3, 1891.

Application filed September 8, 1891. Serial No. 405,136. Term of patent 3½ years. Registered in England September 27, 1890, No. 157,684.

To all whom it may concern:

Be it known that I, ELISHA PECHEY, a subject of Her Majesty the Queen of Great Britain, residing at London, England, have invented and produced a new and original Design for a Font of Type, (which I have registered as a design in Great Britain under date of September 27, 1890, No. 157,684,) of which the following is a specification, reference being had to the accompanying drawing, forming part thereof.

The font of type consists of the usual number of letters, diphthongs, figures, periods, commas, hyphens, and the like, notes of interrogation and exclamation, the pound-sterling symbol, and the ampersand. In the case of the letters B, D, E, F, H, I, J, K, L, N, P, R, U, the diphthongs, and the figures 1 and 4 it will be seen that the vertical strokes are hollowed on the outside of each letter, such hollow having the outline of an obtuse angle slightly rounded at the apex. The diagonal lines of the letters M, V, and W also have this formation. All letters, symbols, and figures whose form will permit of such an ornament—viz., B, C, D, G, J, K, L, P, Q, R, the ampersand, the note of interrogation, the pound-sterling symbol, and the figures 2, 3, 5, 6, 7, and 9—have a curved termination to one or more of their lines. In

the case of the letters A, E, F, L, T, Z, the diphthongs, and the figure 5, either the upper or lower stroke, or both, gradually increase in size in the direction of their extremities and rapidly contract again to a point, the outside lines being in all cases perfectly horizontal. 30

One or more of the limbs of the letters, A, F, H, J, K, L, M, N, P, R, U, V, W, Y and the diphthong AE project above or below the normal gage-line of the letter, such projection terminating in a point. 35

The middle strokes of the letters E, F, and the diphthongs are curved or waved, and the connecting-strokes of the letters A, H, and the diphthong AE are of a double-curved form. The letter F has in addition a curved tail to 45 its middle stroke. The periods, commas, hyphens, and the like are of a flattened oval form.

What I claim is—

The design for a font of printing-type, as herein described and shown. 50

In testimony whereof I have hereunto set my hand in the presence of two subscribing witnesses.

ELISHA PECHEY.
